INTERNAL COMBUSTION ENGINE-
ELECTRIC POWER PLANT

Charles Schaer, Langenthal, Switzerland, assignor to firm Sulzer Frères Societe Anonyme, Winterthur, Switzerland

Application March 17, 1933, Serial No. 661,239
In Switzerland March 22, 1932

4 Claims. (Cl. 290—17)

For internal combustion engines which drive an electric generator it is known to regulate the speed of the internal combustion engine automatically to a substantially constant but adjustable value, in that alterations in load in the region of low loads are compensated by altering the fuel supplied, whilst alterations at higher loads are regulated by adjusting the excitation of the electric generator while the full quantity of fuel continues to be supplied during the regulating operation. This has the drawback that great fluctuations in speed are caused during the regulating operation, so that the regulating takes a long time to carry out.

It is advantageous at all loads not only to effect by the regulating operation a quick alteration of the excitation of the electric generator, but also, in order to accelerate the termination of the regulating, to adjust the fuel delivery during the regulating operation. According to the invention this is effected not only by providing a control device, comprising a supply device dependent on the speed of the internal combustion engine, and a piping system connected with the supply device and automatically controlling, under the influence of a throttle position in the piping system, by means of a power piston connected to the piping piston, a resistance regulating the excitation of the electric generator in such a way that the speed of the internal combustion engine keeps to a substantially constant but adjustable value, but also by a device dependent on the speed of the internal combustion engine adjusting during the regulating operation the regulating member for fuel delivery in a sense opposite to the speed fluctuations of the engine occurring during said operation. The power piston actuating the regulating resistance may, after cutting out the regulating resistance, act on the regulating member for fuel delivery, in order to reduce the fuel supplied from the value set to the consumption for no load.

The invention is illustrated diagrammatically and by way of example in the accompanying drawings in which,

Fig. 1 is a diagrammatic view of an engine-driven electric generator set provided with a hydraulic speed-responsive device arranged to control both the engine fuel-regulating device and the device for controlling the resistance in the excitation circuit of the generator.

Fig. 2 is a similar view of a modification in which the adjustment of the operating speed of the set is made in a different manner, and, in addition, the parts are so arranged that continued

movement of the resistance-controlling mechanism, after the resistance has been reduced to a predetermined value, effects an adjustment of the fuel-regulating device to reduce the fuel supply, and thus automatically enables the speed-responsive device, or governor, to control the speed of the set at light loads.

Fig. 3 is a diagrammatic view showing an engine-electric set wherein the resistance in the generator field is controlled by one speed-responsive device and the fuel-regulating mechanism of the engine is controlled by another speed-responsive device, and

Fig. 4 is a view of an engine-electric set similar to the one shown diagrammatically in Fig. 2 and illustrating a modified means for adjusting the mechanism to produce a change in the torque of the engine without affecting the speed.

In the construction illustrated in Figure 1 the internal combustion engine 1 drives a main generator 2 and an auxiliary generator 3. Though in the construction shown the auxiliary generator 3 supplies the necessary current for the field winding 4 of the main generator 2, the excitation current for the main generator 2 may be provided by a shunt winding or from a separate source. The excitation current flowing through the field winding 4 is regulated, as hereinafter described, by means of a rheostat 5.

The engine 1 drives a pump 6 which tends to circulate pressure medium through a pressure pipe 7, to a return pipe 7' as shown by the arrows in full lines. A throttling point 8 in the pipe 7 can be adjusted by means of a valve 9 actuated by a lever 10 so as to vary the rate of flow of pressure medium from the pressure pipe 7 to the return pipe 7'. The pressure pipe 7 communicates through a branch pipe 11 with a cylinder containing a piston valve 12 which controls the flow of pressure medium from the pressure pipe 7 to a cylinder 13 containing a control piston 14 operatively connected by a rod 15 to the contact arm 16 of the rheostat 5. The pressure pipe 7 also communicates through a second branch pipe 17 with a cylinder 18 wherein can reciprocate a subsidiary piston 19 operatively connected to the piston valve 12 and influenced in the upward direction by a loading spring 20 acting through a piston rod 21. The rod 21 is pivotally connected by means of a link 22 to the fuel regulating device of a fuel pump 23.

The control apparatus, constituted by the pump 6, throttling device 8, valve mechanism comprising the valve 12, subsidiary piston 19 and control piston 14, automatically regulates the ex-

citation current of the main generator 2 so that the speed of the engine 1 is maintained constant at the desired value, as hereinafter described.

The throttle valve 9 is first set by the lever 10, 5 if desired by remote control, in accordance with the speed at which the engine is to operate. When the load on the engine 1 decreases due, for example, to the load on the main generator 2 being decreased, the speed of the engine first increases 10 so that the speed of the pump 6 is increased accordingly. The rate of flow of medium through the throttle 8 from the pressure pipe 7 will remain substantially constant so that the increase in the speed of the pump 6 will result in the pressure in the pressure pipe 7 increasing whereby the valve mechanism comprising the subsidiary piston 19 and piston valve 12 will be forced downwards against the action of the loading spring 20. The piston valve 12 will thus permit 15 pressure medium to flow into the cylinder 13 beneath the control piston 14 whereby this piston will be raised and the resistance 5 decreased. The excitation current of the main generator and therefore the load on the engine will, in this way, be increased and the speed of the engine restored to the desired value in accordance with the setting of the throttle valve 9. The speed of the pump 6 being thus decreased will result in the pressure in the pipe 7 falling to the original or normal value so that the piston 19 will rise under the action of the spring 20 and the piston valve 12 will be returned to its normal or central position shown wherein it cuts off the supply of pressure medium to the control cylinder 13.

When the load on the engine 1 increases, the speed of the engine and therefore the speed of the pump 6 decreases so that the subsidiary piston 19 and piston valve 12 rise from the normal positions shown in Figure 1. Pressure medium thereupon enters the cylinder 13 above the control piston 14 whereby the resistance 5 is increased and the load on the engine decreased. The speed of the engine 1 is in this way restored to the desired value whereupon the subsidiary piston 19 and valve 12 return to their normal or central positions shown. Pressure medium displaced from the cylinder 13 returns through the pipe 7 to the pump 6.

When the subsidiary piston 19 and valve 12 move downwards or upwards due to an increase or decrease respectively in engine speed as above described the resulting movement of the lever 22 simultaneously reduces or increases the quantity of fuel supplied to the engine. The regulation of the plant to restore the engine speed to the desired value is thus effected by simultaneously adjusting the load and the fuel supply. After adjustment of the valve 9 there will be a corresponding pressure on the inlet side of the throttle 8 for any given engine speed. Since however the quantity of medium which can flow through the throttle 8 is in accordance with the setting of the valve 9 the larger the opening of the throttle valve 9 the greater will be the speed at which the engine will be maintained by the control apparatus. The valve 12 will occupy the central or normal position shown, i. e., when it cuts off the supply of pressure medium to the cylinder 13, at a given normal pressure within the pressure pipe 7 that is to say a pressure which balances against the spring 20 when the piston 19 is in the central or normal position shown in the drawings. Thus, by varying the setting of the valve 9 the engine speed necessary to produce the said normal pres-

sure in the pressure pipe 7 will be adjusted accordingly. Since the engine speed necessary to centralize the piston 19 and valve 12 is thus dependent not only on the setting of the valve 9 but also on the tension of the spring 20 adjustment of the speed at which the engine is to operate may be effected by varying the tension of the spring 20 instead of or in addition to adjustment by means of the valve 9.

If desired, the piston 19 may be employed exclusively for actuating the valve 12 and the fuel supply regulated by means of a centrifugal governor 50 (Fig. 3) driven in accordance with the speed of the engine by gearing 51, the tension of the spring 52 loading the governor 50 being simultaneously adjusted preferably through mechanism 53 operatively connected to the lever 10. With a view to limiting the maximum speed of the engine, the spring 52 may load the governor 50 in such a way that the governor 50 acts as a maximum speed safety regulator, cutting off or reducing the fuel supply automatically, if necessary, to the idle running value when the number of revolutions per minute of the engine exceeds a predetermined permissible maximum.

Further, instead of a positive pressure being employed in the pressure pipe 7 to actuate the pistons 19 and 14 a pump, such as the pump 6, may tend to pump the medium in the reverse direction shown by the dotted arrows so that the pressure in the pressure pipe 7 will decrease in accordance with the increase in the speed of the engine thereby operating the pistons 19 and 14 to produce the desired regulation.

In the construction illustrated in Figure 2 the throttling point 8 is not adjustable and the valve 12 is connected to the subsidiary piston 19 by a rod 25 through a lever 26 pivoted at 27 on a block which is internally threaded to engage a correspondingly threaded spindle 28 rotatable by means of a gear 29 so as to adjust the speed at which it is desired that the engine is to be maintained, as hereinafter described. The lower end of the rod 25 is pivotally connected to a lever 30 which is in turn connected by a link 31 to the member 22 whereby the fuel supplied by the fuel pump 21 can be adjusted. The free end 32 of the lever 30 engages a slot in the adjacent end of a lever 33 pivoted on a fixed pivot 34 and connected to a rod 35 which is longitudinally slidable in a sleeve 36 carried by the contact arm 16. The rod 35, which is furnished at its upper end with a stop 37, is loaded by a compression spring 38, the lowermost limit of movement of the rod 35 and therefore of the stop 37 being determined by a second stop 39. The piston valve 12 controls ports in a sleeve 40 which can be adjusted axially by means of an operating rod 41.

Assuming that the parts are in the positions shown in Figure 2, that is to say, with the valve 12 closing the ports in the sleeve 40, and the speed of the engine increases due, for example, to a decrease in the load on the main generator the pressure in the pressure pipe 7 and therefore in the branch pipe 17 will rise as described with reference to Figure 1. The piston 19 will now move upwards against the action of the spring 20 whereby the lever 26 will move the rod 25 downwards. The piston valve 12 is thus moved to admit pressure medium to the cylinder 13 below the control piston 14 which will thus rise and turn the contact arm 16 to reduce the resistance 5 and in this way increase the load on the engine thereby tending to reduce its speed. Simultaneously with this adjustment of the load the down-

ward movement of the rod 25 will act through the link 31 to reduce the fuel supply. The speed of the engine having been thus restored to the desired value the parts will return to their central or normal positions shown. In the event of the engine speed decreasing the sequence of operation of the parts will be the reverse of that above described.

The speed at which the control apparatus is to maintain the engine can be adjusted as desired by means of the gear 29, which may be operated by remote control apparatus. Thus, the speed at which the engine is to be maintained can be increased by turning the spindle 28 so as to raise the pivot point 27 of the lever 26 whereupon the speed of the engine necessary to produce a pressure in the pipe 17 sufficient to move the valve 12 into its central or normal position will be higher, the position of equilibrium being indicated by the position I of the lever 26. Adjustment of the pivot point 27 in this way simultaneously sets the fuel supply to suit the new operating speed of the engine. When it is desired to decrease the speed at which the engine is to be maintained the spindle 28 is turned to lower the pivot point 27 and therefore decrease the engine speed necessary to produce the pressure in the pipe 17 which will move the valve 12 into its normal or central position. The position of equilibrium is then indicated by the position II of the lever 26.

When the speed of the engine increases, due for example to a decrease in the load on the main generator, the upward movement of the piston 14, previously described, causes the block 36 to be moved upwards along the rod 35 until the block 36 engages the stop 37 the arm 16 being in the position III on the resistance 5 which is thus a minimum. If upward movement of the block 36 continues the rod 35 will be moved upwards against the action of the spring 38 and the pivot point 32 of the lever 30 will be moved downwards thereby turning the member 22 so as to reduce the fuel supply. The arrangement is therefore such that when the resistance in the excitation circuit of the main generator has been reduced to the minimum value, i. e., when the contact arm commences to move over the contact 42, the fuel supply is automatically reduced. In this way, in the event of the load on the engine continuing to decrease after the limit of load adjustment by means of the resistance 5 has been reached, increase of the engine speed is checked by reducing the supply of fuel, this decrease in the fuel supply continuing with decrease of the load, if necessary, until the quantity of fuel supplied to the engine is that which corresponds to idle running.

The engine torque may be adjusted, without changing the engine speed, by moving the sleeve valve 40 in the axial direction so as, in effect, to vary the position of the piston valve 12 relatively to the ports through which the pressure medium flows to and from the cylinder 13. The normal or central position of the valve 12 and therefore of the lever 30 and member 22 corresponding to the desired speed of the engine are in this way adjusted. If desired, however, the engine torque may be adjusted by adjusting the operative connection between the member 22 and valve 12. To this end the rod 25 in Fig. 4 is divided into two parts screwed in the female screw 55 which may be turned by the rack 56 connected to the lever 51. By turning the screw 55 the rod 25 is shortened and lengthened, consequently the lever 30 and the member 22 are in this way adjusted

corresponding to the desired speed of the engine.

In a power plant according to the invention the torque on the engine will be maintained substantially constant in spite of variations in the load on the main current generator, the speed of the engine being maintained substantially constant at any value desired with the result that overloading of the engine is prevented. Further, since the pressure medium is constantly circulated through the pipes 7 and 7¹, opening of the valve 12 will result in an immediate effect on piston 14 so that the resistance 5 will be adjusted without delay, which would tend to occur if the pressure medium in the pressure pipe 7 were maintained at rest while the valve 12 is in its central or normal position. Any appreciable variation in the load on the main generator is thus followed so rapidly by adjustment of the excitation current of the main generator that fluctuations in the hauling power or draw-bar pull, with consequent risk of damage to couplings in the case of trains, is avoided. It will further be seen that since the fuel supply to the engine is simultaneously regulated in accordance with the speed of the engine not only is the desired regulation rapidly effected but, in addition, fluctuation of the engine speed is maintained within a small range.

I claim:

1. In combination, an engine, a generator driven thereby, a resistance for regulating the excitation current of said generator, a device for controlling said resistance including fluid supply means dependent upon the engine speed, a fluid circulating system connected with said fluid supply means and a power piston connected with said fluid circulating system for controlling said resistance, a fuel-regulating device, a device responsive to the speed of said engine, means for operatively connecting said speed-responsive device with said resistance-controlling device and said fuel-regulating device to cause the latter to be set during the regulating operation in a sense opposite to the speed fluctuation of said engine occurring during said operation, and means operatively connecting said resistance-controlling device and said fuel-regulating device, said means being operable only after a predetermined amount of said resistance has been cut out so as to reduce the fuel supply to said engine when the load thereon is below a predetermined value.

2. In an engine-electric set including a generator, a resistance for regulating the excitation of the generator, a control device including fluid supply-means dependent upon the engine speed, a fluid-circulating system connected with said fluid supply-means, a power-piston connected with said fluid-circulating system for controlling said resistance, a fuel regulating device for the engine, a pressure-responsive device connected to said system for actuating said fuel-regulating device, and means for adjusting the torque of the engine independently of the engine speed.

3. In an engine-electric set including a generator, a resistance for regulating the excitation of the generator, a control device including fluid supply-means dependent upon the engine speed, a piping system connected with said supply-means, a power-piston for controlling said resistance, a control valve for connecting said power-piston with said piping system, a fuel-regulating device for the engine, a device responsive to the speed of the engine for setting said fuel-regulating device during the regulating operation in a sense opposite to the speed fluctuation of the engine.

engine occurring during said operation, and means for adjusting the torque of the engine independently of the engine speed comprising movable ports for said control valve and means for adjusting the position thereof.

4. In combination, an engine, a generator driven thereby, a resistance for regulating the excitation current of said generator, a device for controlling said resistance including fluid supply-
10 means, a piping system connected with said supply means, a power-piston in the piping system, and a control valve for connecting said power-piston with said piping system, a fuel-regulating device, a device responsive to the speed of said

engine, means for operatively connecting said speed-responsive device with said control valve and said fuel-regulating device to cause the latter to be set during the regulating operation in a sense opposite to the speed fluctuation of said engine occurring during said operation, and means for adjusting the torque of the engine independently of the engine speed comprising means for adjusting the position of said control valve so as to cause said valve to open earlier or later with respect to the movement of said fuel-regulating device by said speed-responsive device.

CHARLES SCHAEER.
